US00D925819S

(12) **United States Design Patent** (10) Patent No.: **US D925,819 S**
(45) Date of Patent: **** Jul. 20, 2021**

(54) **CAR CIGARETTE LIGHTER**

(71) Applicant: **Guangdong BESTEK Medical Devices Co., Ltd.**, Shenzhen (CN)

(72) Inventor: **Xinhua Xu**, Shenzhen (CN)

(73) Assignee: **GUANGDONG BESTEK MEDICAL DEVICES CO., LTD.**, Shenzhen (CN)

(**) Term: **15 Years**

(21) Appl. No.: **29/730,321**

(22) Filed: **Apr. 2, 2020**

(30) **Foreign Application Priority Data**

Dec. 6, 2019 (CN) 201930680517.3

(51) LOC (13) Cl. **27-05**

(57) **CLAIM**

The ornamental design for a car cigarette lighter, as shown and described.

DESCRIPTION

FIG. 1 is a perspective view of a car cigarette lighter showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the car cigarette lighter in a second state.

The broken lines in the drawings are for the purpose of illustrating portions of the car cigarette lighter that form no part of the claimed design.

1 Claim, 9 Drawing Sheets
